PHOTOGRAPHICALLY PRINTING ON MATERIALS

Filed Jan. 17, 1947

UNITED STATES PATENT OFFICE

2,531,086

PHOTOGRAPHICALLY PRINTING ON
MATERIALS

Leize Rose Stewart, New York, N. Y.

Application January 17, 1947, Serial No. 722,694

1 Claim. (Cl. 95—77.5)

1

This invention relates to a process for photographically printing with dyes upon materials such as fabric, leather, paper, plastics, furs and the like, and to an apparatus for employing the said process.

Broadly, it is an object of my invention to provide a continuous process for printing photographically upon materials in one or more colors.

In my invention, the fabric is impregnated with a dye soluble in water and when exposed to light in the presence of air becomes insoluble in water. By the use of a photographic negative which is subjected to light, a fabric impregnated with a dye soluble in water, a photographically printed design corresponding to the negative will be printed upon the fabric or other material. The fabric thus printed is fast to light and is insoluble in water while the dye of the fabric which has not been subjected to the light through a negative in the printing process is soluble in water and is readily removed by a simple washing operation. In this process, it is not necessary to finish the photographically printed areas of the dyed fabric other than the exposure of the dyed fabric to the action of light through the negative.

The dye which has not been acted upon by the light as already stated is easily washed out by a washing operation.

A further object of the invention is to provide a method whereby a fabric may be printed with the same design through a photographic negative on both sides of the fabric.

Still a further object of the invention is to provide a method and device which can photographically produce a design on one side of the fabric and an entirely different design on the opposite side of the fabric.

A further object of the invention is to continually and photographically produce a design in multi-color on one side of the fabric and an entirely different design in multi-color on the opposite side of the same fabric.

Still a further object of the invention is to provide printed material with multi-color designs by overlapping areas of negatives of same design in order to superimpose one area over the other to produce additional colors, such as secondary colors, for example, in printing blue over yellow to obtain an additional color, such as green.

For a fuller understanding of the nature and objects of the invention, reference is had to the following description in connection with the accompanying drawing, in which the figure shown represents a schematic drawing of a continuous process of printing material such as gray goods.

2

The method involved in the process of photographically printing dyed fabrics will be best understood by the following description of the movement of the fabric through the apparatus shown in the drawing, in which parts are broken away for the purpose of better illustration, and in which 11 designates a frame carrying a roll of gray goods 12, which is held upon the frame 11, by means of a shaft 13. A trough 14 is secured upon the frame 11, and contains a sensitizing dye solution 15, and is provided with an angular tray 16, and roller 17, mounted within the tray near the angle thereof.

15 The end of the fabric 12 is fed under the roller 17, and passes from there to opposed squeeze rollers 18 and 19, which are mounted in said frame 11. From the said squeeze rollers 18 and 19, the fabric passes under a guide roller 20, and over a guide roller 21, both of which rollers are mounted upon a second frame 22. The fabric then passes over a series of rollers 23, upon the said frame 22, the said rollers having pins 23' upon their outer peripheries which are adapted to engage the selvage of the fabric as same moves along.

From the pin rollers 23, the fabric passes under and moves with a transparent cylinder 24 of glass or other suitable transparent material, within which are suitably mounted high power lighting units 25 which move with the said cylinder 24 as it revolves upon its carrying shaft 26. The said fabric 12 then passes around and moves with a second transparent cylinder 27, which rotates in a direction opposite to the rotating movement of the cylinder 24. The said second cylinder 27 is also provided with high power lighting units 28, and is rotatively mounted upon a shaft 29. Both of the said cylinders are carried upon the frame 22, and rotary motion is given the cylinders by means of a motor 30, connecting belt 31, pulleys 32, 33 and 34, connecting belt 35, double grooved pulley 34', crossed belt 36 and pulley 36'.

40 From the transparent cylinder 27, the fabric passes over a guide roller 37, and thence down to and under a roller 38, mounted in a tray 39, thence up to a roller 40, mounted upon a frame 41, constituting a part of a washing mechanism. From the roller 40 the fabric passes downwardly and upwardly in successive order in the following manner: under the roller 42, which is mounted in a tray 43, over the roller 44, under the roller 45 in a tray 46, over the roller 47, under a roller 48 in a tray 49, and thence upwardly to and around a framing and drying drum 50.

45 50 The said framing and drying drum 50 is ro-

tatably mounted in a frame 51, and is provided with pins 50', which grip the selvage of the fabric to dry and stretch it to its original size. The fabric, after moving around with the said drying drum 50, passes around and under a guide roller 52, to a second drying and finishing drum 53. The finished fabric is then wound upon a roll 54.

A storage tank 55 is mounted upon the aforesaid frame 11, and carries a sensitizing dye solution which may be fed to the trough 14, through an outlet 56, having a valve 57.

Under the trays 39, 43, 46 and 48, there is provided an overall tray 58, having a drawoff cock 59. A water supply pipe 60 is suitably attached to the upper portion of the frame 41, and has depending branches 61 having water outlets 62, through which water may be sprayed upon one side of the fabric as it moves between the upper and lower rollers of the washing apparatus. Extending upwardly from the tray 58 there is a second series of water pipes 63, having outlets 64, through which water may be sprayed upon the reverse side of the fabric as it moves between the said upper and lower rollers. Means may be provided to produce a soapy water in the first or second tray through which the fabric passes during its progress. A receptacle 61' may be interposed in one or more of the said water-spraying pipes, and employed to saponify the water emitted from said pipes. Suitable means (not shown) may be provided to rotate the drying drums and the rollers of the washing mechanism.

With the method and apparatus herewith disclosed, a fabric may be photographically printed upon one or both sides. When the fabric is to be printed upon one side, the cylinder 24 is used for photographically imprinting a figure or design upon same. When, however, both sides of the fabric are to be photographically imprinted, both cylinders 24 and 27, are employed.

The dye sensitizer used in the tank 55, is heated either before it is placed therein or while the sensitizer is in the trough. Such dye is normally soluble in water and rendered insoluble by being subjected to the action of light. Dyes with this property are esters of leuco combinations of vat dyes, the salts of esters of leuco combinations of vat dyes being preferred. The leuco esters combinations, or compounds are available in a wide range of colors.

In order to prepare the right sensitizer dye solution, the solution of the esters of leuco compounds of vat dyes is dissolved in water at a temperature of approximately 150° F. in the proportion of about 20 grams of dye to 1 liter of water. For the color brown, warmer water is used, specifically water at a temperature of 180° F. In the case of certain dyes, 4 cc. of formic acid per liter of the dye solution is added. The addition of formic acid in the above mentioned quantity accelerates the action of the light on the dye and renders the later insoluble, except, however, in the case of a color where the action of light is relatively slow. In some instances it has been found that the use of hygroscopic agents such as glycerine, and particularly urea, have a favorable accelerating influence.

The solution in trough 14 at the time of emersion of the material may be at ordinary room temperature except when a less soluble dye, such as a brown dye is used, at which time the solution is kept at a temperature preferably of 140° F. since the brown dye has a tendency to crystallize at room temperature.

Assuming that the upper side of the fabric is to be photographically imprinted, a negative is suitably attached against the outer surface of the glass cylinder 24, and the units 25 lighted. Sensitized dye solution is fed from the tank 55, into the trough 14, and the fabric 12 is fed through the apparatus as already described. As the fabric passes through the sensitizing dye solution 15, in the trough 14, it becomes impregnated with the solution and is then passed between the squeeze rollers 18 and 19, where the excess dye solution is pressed out and allowed to drip upon an extension 17', of the said angular tray 16, from whence it drains into the trough 14. After passing through the said squeeze rollers the fabric is led over the pin rollers 23-23' to and under the transparent cylinder 24, around and with which it turns while the rays from the light unit 25 pass through the negative upon the said cylinder exposing parts of the sensitized fabric to the action of the said light rays, and wherever said light rays pass through the negative, the parts of the fabric affected by the light rays are rendered insoluble, while the parts unaffected by the light rays remain soluble and are easily washed away.

The washing process is accomplished by passing the fabric through a series of tanks 39, 43, 46 and 48, one or more of which may contain saponified water while subsequent tanks may hold clear water. Supplementing the water in the tanks are the said sprayer pipes 61, which spray addition water upon the upper surface of the fabric.

From the washing mechanism the fabric passes to the drying and framing drum 50, which drum has a series of pins 51' arranged along the outer edges thereof and adapted to pierce and grip the selvage of the fabric, thus drying and stretching the fabric to its original size. From the drum 50, the fabric passes to and around a second drying drum 53, where it is finished. It is then wound upon a roll 54.

The washing tray 58 is adapted to collect the overflow water from the trays 39, 43, 45 and 48, and may be drawn off through the drawoff tap 59.

To print upon both sides of the fabric, the second cylinder 27 is brought into play. A negative is suitably attached thereon and the light units within the said cylinder 27, are turned on, thus bringing both cylinders 24 and 27, into action. The fabric passes through the sensitizing dye solution in trough 14, squeeze rollers 18 and 19, and over the rollers 23-23', to and around the said cylinders 24 and 27, where the light rays will act upon the exposed parts on both sides of the sensitized fabric in the manner already described for a single printing operation. From the cylinders 24 and 27, the fabric passes through the washing unit, around the drying drums 50 and 53, to the finished roll 54. Both sides of the doubly printed fabric must be washed, and for this purpose the spraying pipe 64, as well as the spraying pipe 61, are utilized.

Depending upon the character of the fabric or material which has been photographically printed, it may be necessary to use additional framing and drying drums similar to drum 54, in order to thoroughly dry the material and stretch it to its original size.

If more than one color is desired for printing on one side the finished roll of material 54 is passed through a set of the identical equipment hereinbefore described except that a part of the photographic negative, or design carrying film which

is mounted on the outer surface of the cylinder is blocked out so that the remaining portion of the design may be printed. Instead of using the same dye color sensitizer, another dye color sensitizer is used; for example, if the first color printed is yellow, the second color may be printed in blue, and if it is desired to overlap the blue with the yellow in order to create green the photographic negative has its area so blocked out that certain portions of the design will overlap portions of the design of the first negative.

In some instances it is desirable to have the design printed on both sides of the fabric as, for instance, on ladies' scarves. To accomplish this, similar negatives are used on both transparent cylinders 24 and 27, but attached to the cylinders in reversed order, and the fabric passed between the said cylinders. The negatives must be so positioned upon the cylinders 24 and 27, that the design on the two sides of the fabric will register or mesh.

On certain types of fabrics it may be desirable to print multicolor designs on both sides of the material, the design on each side being different. In such cases, the photographic negatives on the rollers 24 and 27, are of different design, around which rollers the fabric may be passed and similar colors of both designs may be printed simultaneously on both faces of the material.

The speed of the revolutions of the various rollers, such as the squeezing rollers 13 and 19, rollers 23-23', and cylinders 24 and 27, are so synchronized as to move the material continuously along at a uniform rate.

It will be understood in the operation of the apparatus hereinbefore described the material is progressively passed between the cylinders 24 and 27, so that the light rays pass through the negatives and act upon the entire length of the sensitized fabric. After the sensitized fabric is photographically printed it is first washed in clear water at a temperature of 150° F. Thereafter, if desired, the fabric may be washed in soapy water at about the same temperature until the unexposed sensitizing dye has been removed. During the washing process, a piece of fabric may be tested by exposure to light and if the exposure produces no change in the color of the fabric the complete removal of the surplus dye is indicated.

The process of photographically imprinting fabrics as described may also be used upon silks, rayons, cotton and linen, and fabrics containing a mixture of those already mentioned. This process is also applicable for photographically printing on leather, plastic and other like materials.

In the process described it is not only unnecessary to fix the dye after the latter has been ex-

posed to the light but the printed fabric can be freely handled in such a manner as to facilitate production thereof and to simplify the manufacturing operations. The process, as described, makes possible continuous printing with the dye impregnated fabric in either wet or dry condition, and enables a continuous printing of repeat units of a design on successive portions along the lengths of the fabric very similar to roll printing with engraving rollers.

While the preferred embodiment and method of practising the invention are herein disclosed, it is understood that the invention is susceptible to various changes, modifications and additions without departing from the general spirit of same.

I claim:

In apparatus for photographically dye printing sheet material, the combination with a rotatable transparent cylinder having a negative mounted on the wall of said cylinder and a source of light mounted interiorly of the cylinder, means for supporting a roll of said sheet material, means for impregnating said sheet material with a water soluble, light sensitive dye, means for moving the sensitized sheet material into surface contact with wall of said cylinder whereby exposed portions of the sensitized sheet material have their dye impregnant rendered water insoluble and the unexposed portions of the sensitized sheet material have their dye impregnant remaining water soluble, means for removing the water soluble dye impregnant from the exposed sheet material comprising spray means for directly applying washing solution to at least one surface of the sheet material and a container for receiving the washing solution from the spray means, means for advancing the sprayed sheet material through said container and into contact with washing solution within the container to insure complete removal of water soluble dye impregnant from the exposed sheet material and means for drying the washed, exposed sheet material.
